UNITED STATES PATENT OFFICE.

WILLIAM E. WINE, OF TOLEDO, OHIO.

CAR-DOOR-LOCKING DEVICE.

Application filed January 12, 1922. Serial No. 528,650.

My invention relates to new and useful improvements in car door locking devices and has for an object to provide a car door locking device that is extremely simple in construction and operation.

Still another object of the present invention is to provide a locking device that is especially adapted for use on freight cars having drop bottom doors, which doors are to be swung upwardly by hand and then engaged by a hook, the hook preferably cooperating with an angle or other member secured to the bottom of the door and extending transversely thereof and beyond the free side of the door.

Still another object of the invention is to provide a locking device comprising a base or bracket which is designed to be secured to the car body, this bracket or base having formed integrally thereon a guard or housing in which the hook is pivotally mounted, which housing completely encloses the upper edges of the hook and partly encloses the shank of the hook.

Still another object of the invention is to provide a locking device for drop doors, compact in nature and preventing transverse or lateral movement of the hook of the locking device.

With these and other objects in view, the invention consists in certain new and novel arrangement and combination of parts as will be hereinafter more fully described and pointed out in the claims.

Referring now to the drawings, showing a preferred embodiment of the invention—

Fig. 1 is a side elevation of my locking device showing a fragmentary portion of a side of a car and one side of a door, the door being held in its locked position.

Fig. 2 is a sectional view taken on line 2—2 of Fig. 1.

Fig. 3 is a sectional view taken on line 3—3 of Fig. 1, and

Fig. 4 is a perspective view of the base or bracket of the locking device.

Referring now to the several figures, there is shown a fragmentary portion 1, of the side of a car, a bracket 2 which is secured to a center sill (not shown) from which in turn is hinged the door 3 and to which door and near its outer end thereof, is secured the angle iron 4 which extends beyond the free edge of the door as clearly shown in Fig. 2.

This angle iron 4 is a convenient form of ledge for the door and is to be supported by

the hook 5 of the locking device, but it is to be understood that other forms of angles 4 or sections, might be used instead of the form shown in the drawing.

60

Riveted or bolted to the side of the car above the angle 4 on the door 3 is the base or bracket 6 of the locking device which may be rectangular in shape and provided with bosses 7 near its opposite corners which, of course, are drilled for the reception of rivets 8. Fastened on the inner side of the car body may be a plate 9 through which the lower rivets 8 may pass, which plate, of course, reinforces the side of the car at this point.

65

On the upper edge of the base 6 there is formed the semicircular projection 10 over which is provided the integral housing 11, which housing and projection are provided with the opening 12 through which is passed a bolt 13 on which bolt is hung the hook 5 that is provided with the opening 14 at its upper end. This bolt 13 also is passed through the side 1 of the car body and is held in place by the nut 15.

70

On the upper edge of the base 6 there is formed the semicircular projection 10 over which is provided the integral housing 11, which housing and projection are provided with the opening 12 through which is passed a bolt 13 on which bolt is hung the hook 5 that is provided with the opening 14 at its upper end. This bolt 13 also is passed through the side 1 of the car body and is held in place by the nut 15.

75

The housing 11 or guard, as will be clearly seen in Fig. 4, tapers to a point 16 at its lower end, it being open along its rear edge so that a dog 17 may be jammed against the rear edge of the hook 5 when said hook is in its closed position, as clearly shown in Fig. 1.

80

This housing or guard 11 prevents any looseness or lateral play of the hook, especially at its upper end, and also throughout its greater portion, and at the same time, by being open at its rear the movement of the hook is in no way limited, rearwardly, and the dog 17 can be quickly and readily jammed into position.

90

The guard may be reinforced by the rib 18 and further ribs or reinforcements might be easily added, if desired.

95

It is to be understood that although I have shown the guard or housing 11 tapered to the point 16, it might be made without tapering and extend completely across the shank of the hook just so long as the rear edge is not joined with the base 6, in such a manner as would interfere with the rotation of the dog 17 into its securing position behind the hook.

100

The operation of the device is exceedingly simple: Supposing the door is in its locked position, to unlock the same, it is first only necessary to swing the dog 17 rearwardly

110

and knock the hook 5 from beneath the leg of the angle 4, and to lock the door, of course, the operation is simply reversed.

From the foregoing it will be seen that I have provided a locking means that is exceedingly simple in construction, may be readily and quickly applied to freight cars and is easily operated to lock the door and tightly hold the same in its locked position.

10 In the drawing, I have shown only one side of a car and one locking device, but it will be understood that in numbers of instances, a similar arrangement will be used on the opposite sides of the car and door so that the door will be supported and locked from both of its outer ends.

By forming the bracket with integral spaced inner and outer walls, in both of which the pivot pin 13 has bearing, it will be seen that the pin 13 will be held in a rigid manner so that no undue looseness of the hook can develop in service from relative movement between the inner and outer bearings for the pivot pin. Furthermore, the integral end wall that unites the inner and outer walls to form the housing is arranged to follow the lines of the forward edge of the hook when it is in its extreme forward position, so that the unsupported area of the outer wall 11 is reduced to a minimum and also a stop is provided within the bracket itself for the hook. The arcuate upper end 10 of the connecting wall follows around the circular end of the hook above the pivot point thereof so that the downward force from the load of the pin 13 will be resisted in part by this joining metal located in hood fashion above the pivot pin. And it will also be noticed that by diverting the connecting wall 35 in this manner, it follows an angular path so that the housing 11 is joined to the inner wall or base 6 by an upright connecting wall of extremely light weight and yet of great strength in all directions. This is of importance as the casting is frequently subjected to abuse such as being struck by a hammer or a bar by the workmen.

By making the outer wall 11 of less extent than the inner wall, the rivets for securing the bracket to the car may pass through the inner wall only, thus making them easier to drive and of less weight than were they passed through a greater grip of material. The rivet forming the pivot point of the dog 17 is preferably loosely driven to avoid

clamping the dog against the face of the bracket, hence this rivet offers but little resistance against slippage of the bracket. The other three rivets, however, may be securely driven, two of them lying to one side of the hook and along the edge of the hook. The rivets are thus arranged to balance the forces from the hook and will hold the bracket against slippage or rotation, while, at the same time the rivets, particularly the two important ones lying along the connecting walls of metal, pass through the bracket at points especially able to withstand the concentration of rivet pressures.

It will thus be seen that in the arrangement as shown and described, I have produced a door-locking mechanism of extremely simple construction, but at the same time with the elements so arranged that no metal is wasted and the device is of extremely light weight. This is important as the general effort of today is to reduce the dead weight of freight cars. My device is especially desirable from this point of view.

Many slight changes might be made without in any way departing from the spirit and scope of the invention.

Having thus described my invention, what I claim as new and desire to secure by Letters Patent is:

1. A locking device for drop doors comprising a base, a tapered housing formed integral with said base and said housing open along its rear edge, a hook pivotally mounted in the housing said housing enclosing both the upper edge of said hook and a portion of the shank of said hook, and means for holding the hook forwardly in said housing in its locked position.

2. A locking device for drop doors embodying an inner wall of metal, an outer wall of metal integral therewith, a hook having a pivot eye at the upper extremity of its shank, the said eye portion of the shank lying between the said integral walls, a pivot member extending through both walls and through the eye of the hook, an integral end wall of metal joining the outer and inner walls, the same approximately defining an edge and the top of the shank of the hook, and a dog pivoted upon one of the said walls and arranged to hold the hook in a forward position near the said end wall.

In testimony whereof I affix my signature.

WILLIAM E. WINE.
